CLAIM

The ornamental design for a tent structure, as shown and described.

DESCRIPTION

FIG. 1 is a perspective view of a tent structure;

FIG. 2 is a perspective view of a tent structure with the front panel removed;

FIG. 3 is a front view of a tent structure;

FIG. 4 is a rear view of a tent structure; and,

FIG. 5 is a side view of a tent structure.

The broken lines are for illustrative purposes only and form no part of the claimed design.
